CLAIM

The ornamental design for an interface cassette for printer, as shown and described.

DESCRIPTION

FIG. 1 is a top, front and left side perspective view of an interface cassette for printer showing my new design, FIG. 2 is a bottom, rear and left side perspective view thereof,

FIG. 3 is a front elevational view thereof,

FIG. 4 is a rear elevational view thereof,

FIG. 5 is a top plan view thereof,

FIG. 6 is a bottom plan view thereof,

FIG. 7 is a left side elevational view thereof,

FIG. 8 is a right side elevational view thereof, and

FIG. 9 is a perspective thereof showing the interface cassette in its operational environment, the printer being shown in broken lines for illustrative purposes only.
